 Florence Pipe Foundry & Machine Company,
 Florence, N. J., a corporation of New Jersey

Application April 4, 1941, Serial No. 386,830

6 Claims. (Cl. 18—17)

This invention relates to presses, and is especially adaptable and advantageous for long presses, such as are used for treating belting or fabric in long lengths, like rubberized conveyor belting or other belting. The invention is particularly concerned with guiding and controlling the movable pressure-applying member or follower of such a press. Important objects of the invention are to provide guidance for the motion of such a follower to keep it in proper correspondence with the coacting pressure-applying member of the press structure; to prevent such a follower from skewing in its own plane; and to prevent such a follower from skewing or cocking in transverse or longitudinal planes perpendicular to its own plane. In suitable forms of embodiment, the invention permits of realizing any or all of these purposes in a press.

Presses for the manufacture of rubberized belting or the like are of considerable length and involve the application of pressure on considerable areas, so that the forces involved are very considerable. Such presses are commonly arranged with their platens horizontal, and the upper and lower pressure-resisting structures of the press are interconnected by rows or series of massive upright tie-rods or columns along opposite sides of the press. Considerable heat may be applied in such presses, for the purpose of softening or of curing or vulcanizing the material treated. As the press may be as much as some thirty feet long or over, and as the treating temperature may be fairly high, the coacting pressure-applying members of the press are subject to substantial thermal change in length, which may be of the order of three-fourths inch, more or less.

For the purpose of accommodating and freely permitting such thermal change in the press follower while guiding its movements up and down, I employ guides suitably distributed or located in its length, and coacting with tie-rods at opposite edges of the follower, these guides engaging around their tie-rods and preferably surrounding them completely, and also embracing or engaging above and below portions of the corresponding edges of the follower, but not being fixed to it in any way. Of course the relations of engagement between the guides and the follower edges may be reversed, so that projection(s) on the guide(s) engage in groove(s) in the edge(s) of the follower; or various other more or less equivalent forms of tongue and groove engagement may be employed, so long as oppositely

5 facing transverse shoulders on a guide engage with (either around or between) corresponding longitudinal shoulders on the follower against displacement of the guide lengthwise of its tie-rod relative to the follower. Such change-permitting guides may be located wherever most desirable in the length of the follower, as on the tie-rods at one or both ends of the two series or rows above mentioned.

10 Other guides may be provided on the opposite edges of the follower for coacting with corresponding tie-rods, these latter guides being attached or fixed to the follower and engaging around their tie-rods sufficiently to control the position of the follower portion to which they are attached lengthwise of the tie-rods, though not necessarily surrounding the latter.

15 With respect to the interrelations of the two types of guides, the position-controlling guides may be located at any points suitably removed from the change-permitting guides: e. g., the position-controlling guides might be at one end of the series of tie-rods, and the change-permitting guides at the other end thereof; or the position-controlling guides may coact with mid tie-rods (i. e., tie-rods at or near the middle of each series), and the change-permitting guides may coact with end tie-rods (i. e., tie-rods at or near the opposite ends of each series).

20 25 30 When guides of these two types are suitably constructed and applied in conjunction, as explained hereinafter, they keep the follower in proper correspondence with the coacting pressure-member by controlling its position both lengthwise and transversely with respect to this member and to the press tie-rods; they prevent the follower from skewing in its own plane; and they also (especially the change-permitting guides) resist skewing or cocking of the follower

35 40 45 50 in the transverse planes defined by corresponding tie-rods of the two series. To reinforce the resistance of the guides to skewing or cocking of the follower in longitudinal planes parallel with the two series of tie-rods, I preferably provide coacting motion-equalizing means connected to the opposite ends of the follower, such, for example, as toothed rack-bars each attached to the rear of the follower near an end thereof and meshing with a toothed pinion fast on one end of a sufficiently stout longitudinal shaft mounted in suitable bearings attached to pressure-resisting structure of the press.

Various other features and advantages of the invention will become apparent from the follow-

ing description of a species or form of embodiment, and from the drawings. Indeed, all the features and combinations shown or described are of my invention, so far as they are novel.

In the drawings, Fig. 1 is a side view of a belt-making type of press conveniently embodying the invention, intermediate portions of the press being broken out at two points to allow of showing the essential parts on a reasonable scale, and the breaks being taken through pressure cylinders of the press in both instances.

Fig. 2 is an end view of the press from the right of Fig. 1; but in its left-hand half it shows the press mainly in vertical cross-section taken through one of its pressure cylinders.

Fig. 3 is a fragmentary side view of one of the position-controlling guides of the press, part of the guide and press follower structure being broken out and in section; and Fig. 4 is a fragmentary plan and section view showing this guide and part of the follower in section as indicated by the line and arrows IV-IV in Fig. 1.

Fig. 5 is a fragmentary plan and sectional view of one of the change-permitting guides and part of the press-follower, taken as indicated by the line and arrows V-V in Fig. 1.

As shown in Figs. 1 and 2, the press comprises top and bottom pressure-resisting structures 10 and 11 interconnected by series or rows of upright tie-rods or columns 12 along opposite sides of the press. In the present instance, the top and bottom structures 10 and 11 each consist of a series of transverse top and bottom cross-girders or heads, and corresponding tie-rods 12, 12 of the two series interconnect the opposite ends of corresponding top and bottom girders. The frame-like units formed by corresponding upper and lower girder-heads 10, 11 and columns 12, 12 may be interconnected and suitably spaced by longitudinal tie-rods 13 whose ends are suitably secured through lugs or ears 14 on opposite ends of the girder-heads. The lower girder-heads 11 are shown resting on a pair of longitudinal rails 141, 141 that extend the whole length of the press, and may be made in sections and bolted together at 142. The upper and lower pressure-applying members or plattens 15 and 16 extend along the whole length of the press, the upper member 15 bearing upward against the upper heads 10, and the lower member 16 resting on a rigid follower 20 that also extends the whole length of the press. The plattens 15, 16 may be held to the structures 10 and 20 with freedom for thermal expansion and contraction (especially lengthwise) by any suitable means, such as brackets 21, 22 bolted to said structures 10, 20 at suitable points in the length of the press and engaging under and over projecting lugs 23, 24 on the edges of said plattens. Any convenient means for heating either or both plattens 15, 16 (directly or indirectly) may be employed, such as steam supplied through any suitable connections, not shown.

Pressure may be exerted between the top and bottom structures 10, 11 by means of suitably arranged press cylinders 25 with pistons or plungers 26. As shown, two cylinders 25, 25 symmetrically located at opposite sides of the longitudinal center-line of the press rest on each of the lower heads 11, while their plungers 26 bear against the lower side of the follower 20. Pressure fluid may be admitted and vented to and from the lower ends of the cylinders 25 through pipes 27 connected to a suitable system of piping and control valve means, not here shown.

The parts thus far described are essentially old,

and have been explained as a background for the understanding of my present invention.

To control the lengthwise and transverse position of the lower pressure-applying member 16 and the follower 20 relative to the upper pressure-applying member 15, the structure 10, and the tie-rods 12, guides 30 are shown attached to the mid-portion of the follower 20 at its opposite edges, for abutting against the inner sides of corresponding mid tie-rods 12a, 12a and engaging around them at least part way. As shown in Figs. 3 and 4, these guides 30 consist of metal blocks that are seated and secured against the edges of the follower 20 by bolts 31, and have in their outer sides (preferably) semi-circular recesses conformable to the (preferably) circular tie-rods 12a which they engage. As shown in Figs. 3 and 4, readily changeable shim-plates 33 are interposed between the backs of the guide blocks 30 and their projecting seats 34 on the edges of the follower 20, as a means of taking up any looseness (arising from wear, for example) that would allow objectionable transverse play of the follower between the tie-rods 12a, 12a at its opposite edges. Besides controlling the positions of the follower 20 as already mentioned, the guides 30 also tend to resist skewing or cocking of the follower in transverse vertical planes defined by corresponding tie-rods 12 of the two series, as well as skewing of the follower in its own horizontal plane.

As here shown, the vertical length of the guide blocks 30 exceeds the vertical thickness of the follower 20, and the lower ends of the blocks are thickened rearward to afford shoulders 35 that engage under the lower corners of the follower. The guides 30 may have removable semi-circular liners or wear-plates 36 for engaging the tie-rods 12a, with end flanges or shoulders 37 for engaging corresponding rabbet-shoulders at the upper and lower ends of the guide blocks. These liners 36 may be held in place in the semi-circular recesses of the blocks 30 by means of plates 38 bolted to the blocks at either side of the recesses and overlapping the edges of the liners.

To guide and control the follower 20 most effectually against horizontal skewing in its own plane, and also against skewing or cocking in the transverse vertical planes of corresponding tie-rods 12, 12 of the two series, guides 40 are shown mounted at opposite ends of the follower, on both edges thereof, for coaxing with corresponding end tie-rods 12b, 12b, 12b, 12b. As shown in Figs. 2 and 5, these guides 40 not only engage around the tie-rods 12b at the inner sides of these tie-rods and abut against raised seats 41 on the edges of the follower 20, but they embrace the tie-rods 12b and even surround them completely. As shown in Fig. 5, the guides 40 have (preferably) cylindrical bores conformable to the (preferably) cylindrical tie-rods 12b. Instead of being attached to the follower 20, as are the guides 30, the guides 40 are shown in Fig. 2 as grooved or shouldered at 42, 43 above and below the seat portion 41 of the follower edge, so as to embrace this edge portion of the follower snugly but not tightly. Thus the guides 40 leave the ends of the follower 20 free for longitudinal movement relative to the end tie-rods 12 when thermal changes in the length of the follower occur.

For convenience in assembly, the lower shoulder 43 of each guide 40 is shown as consisting of a separate plate detachably secured to the lower end of the guide 40, as by bolts 45; and the guide

is shown as made in halves divided on a vertical longitudinal plane through the axis of its tie-rod 12b and detachably secured together by bolts 46. As shown in Figs. 2 and 5, the halves of the guide 40 have horizontal key and groove inter-engagement at 47 to facilitate correct assembly. Readily changeable shim-plates 48 are shown interposed between the guide halves, as a means of taking up any looseness and play (arising from wear, for example) that would tend to allow 10 cocking of the follower 20 relative to the tie-rods 12 in transverse vertical planes. The halves of the guide 40 may have removable (substantially) semi-circular liners or wear-plates 50, 50 for engaging the tie-rod 12b, with end flanges 15 or shoulders 51 at their lower ends for engaging corresponding rabbet-shoulders at the lower ends of the guide halves. These liners 50, 50 may be held in place in the guide 40 by means of the plates 43 already mentioned and other 20 plates 52 bolted to the lower ends of the guide halves and overlapping the lower ends of the liners, as best shown in Fig. 2.

To aid or reinforce the control of the follower 20 against cocking in vertical longitudinal planes 25 parallel with the series of tie-rods 12 that is afforded by the guides 30 and 40, motion-equalizing means are shown in Figs. 1 and 2 as connected to and interconnecting the opposite ends 30 of the follower. The form of equalizing means 35 here illustrated comprises upright toothed rack-bars 55 having their upper ends secured to the rear or bottom side of the follower 20 by fastenings 56, and meshing with toothed pinions 57 fast on opposite ends of a horizontal longitudinal 35 shaft 58 mounted in bearing brackets 59 up-standing from and attached to the lower structure 11 of the press.

Having thus described my invention, I claim:

1. The combination with two spaced series of 40 press tie-rods and a press follower extending lengthwise between said two series of tie-rods for coaction with a pressure-resisting structure held by said tie-rods, of guides embracing said tie-rods at opposite ends of both series, said guides 45 being wholly exterior to the follower and having oppositely facing transverse shoulders engaged with corresponding longitudinal shoulders on the follower to prevent displacement of the guides relative to the follower lengthwise of their tie-rods, while leaving the follower free for unlimited longitudinal movement relative to said tie-rods and guides when thermal changes in the length of the follower occur.

2. The combination with two spaced series of 55 press tie-rods and a press follower extending lengthwise between said two series of tie-rods for coaction with a pressure-resisting structure held by said tie-rods; of guides embracing said tie-rods at opposite ends of both series, said guides being wholly exterior to the follower and having oppositely facing transverse shoulders engaged with corresponding longitudinal shoulders on the follower to prevent displacement of the guides relative to the follower lengthwise of their tie-rods, whereby they resist skewing of the follower in the transverse planes of corresponding tie-rods of the series, as well as in its own plane, while leaving the follower free for unlimited longitudinal movement relative to said tie-rods and guides when thermal changes in the length of the follower occur; and motion-equalizing means connected to the opposite ends of 60 said follower for resisting skewing of the fol-

lower in a longitudinal plane parallel with said series of tie-rods.

3. The combination with two spaced series of 5 press tie-rods and a press follower extending lengthwise between said two series of tie-rods for coaction with a pressure-resisting structure held by said tie-rods, of guides attached to said follower at its opposite edges for abutting against and engaging around tie-rods of said two series, to control the position of said follower both lengthwise and transversely with respect to said tie-rods, and other guides embracing tie-rods of said series remote from those engaged by the first-mentioned guides, the last-mentioned guides being wholly exterior to the follower and having oppositely facing transverse shoulders engaged with corresponding longitudinal shoulders on the follower to prevent displacement of the guides relative to the follower lengthwise of their tie-rods, while leaving the follower free for unlimited longitudinal movement relative to said last-mentioned tie-rods and guides when thermal changes in the length of the follower occur.

4. The combination with two spaced series of 25 press tie-rods and a press follower extending lengthwise between said two series of tie-rods for coaction with a pressure-resisting structure held by said tie-rods, of guides attached to said follower at its opposite edges for abutting against and engaging around mid tie-rods of said series, to control the position of the mid-portion of said follower both lengthwise and transversely with respect to said tie-rods, and other guides embracing tie-rods at opposite ends of both series, the last-mentioned guides being wholly exterior to the follower and having oppositely facing transverse shoulders engaged with corresponding longitudinal shoulders on the follower to prevent displacement of the guides relative to the follower lengthwise of their tie-rods, whereby they resist skewing of the follower in the transverse planes of corresponding tie-rods of the series, as well as in its own plane, while leaving the follower ends free for unlimited longitudinal movement relative to said last-mentioned tie-rods and guides when thermal changes in the length of the follower occur.

5. The combination with two spaced series of 50 press tie-rods and a press follower extending lengthwise between said two series of tie-rods for coaction with a pressure-resisting structure held by said tie-rods, of guides attached to said follower at its opposite edges for abutting against and engaging around mid tie-rods of said series, to control the position of the mid-portion of said follower both lengthwise and transversely with respect to said tie-rods, and other guides wholly exterior to the follower embracing tie-rods at opposite ends of both series and embracing the corresponding edges of said follower, whereby they resist skewing of the follower in the transverse planes of corresponding tie-rods of the series, as well as in its own plane, while leaving the follower ends free for unlimited longitudinal movement relative to said last-mentioned tie-rods and guides when thermal changes in the length of the follower occur.

6. The combination with two spaced series of 70 press tie-rods and a press follower extending lengthwise between said two series of tie-rods for coaction with a pressure-resisting structure held by said tie-rods; of guides attached to said follower at its opposite edges for abutting against and engaging around mid tie-rods of said series, to control the position of the mid-portion of said

follower both lengthwise and transversely with respect to said tie-rods; other guides wholly exterior to the follower embracing tie-rods at opposite ends of both series, the last-mentioned guides having oppositely facing transverse shoulders engaged with corresponding longitudinal shoulders on the follower to prevent displacement of the guides relative to the follower lengthwise of their tie-rods, whereby they resist skewing of the follower in the transverse planes 10

of corresponding tie-rods of the series, as well as in its own plane, while leaving the follower ends free for unlimited longitudinal movement relative to said last-mentioned tie-rods and guides when thermal changes in the length of the follower occur; and motion-equalizing means connected to the opposite ends of said follower for resisting skewing of the follower in a longitudinal plane parallel with said series of tie-rods.

LOUIS A. CAMEROTA.
